SMOKING PIPE

Filed Jan. 11, 1928

Fig. 4

Inventor:
Jerome Gevirmam
by Maurice S. Gayne
Atty:

UNITED STATES PATENT OFFICE.

JEROME GEVIRMAN, OF CHICAGO, ILLINOIS, ASSIGNOR TO WESTERN BRIAR PIPE COMPANY, OF CHICAGO, ILLINOIS, A CORPORATION OF ILLINOIS.

SMOKING PIPE.

Application filed January 11, 1928. Serial No. 245,883.

The invention relates to improvements in smoking pipes, and has particular reference to those pipes made of a phenol resin compound, or the like.

The object of the present invention is to improve the construction described so as to reinforce the same in a manner that will materially reduce the liability of injury thereto either by becoming overheated in use or by negligent handling of the same, permitting the same to drop or fall to the floor, and which will maintain the pipe in a useful and uninjured or undamaged condition for a longer period than has been customary heretofore.

The main difficulty with pipes of this character is that the bowl thereof quickly becomes overheated in use and begins to crack, or is otherwise damaged, rendering the pipe useless. Attempts have been made to reinforce the bowl of the pipe, and other means have been proposed for preventing the cracking or otherwise injuring the bowl of the pipe. But even then difficulty has been experienced in making a sufficiently secure connection between the bowl of the pipe and the inner reinforcing bowl to prevent the formation of an air compartment therein, which is the case when the inner bowl is screwed into the outer bowl, the said air compartment causing a cracking of the outer bowl when the same becomes overheated. Another difficulty is that the stem of the pipe which is generally internally threaded at the end thereof, to receive a suitable mouthpiece, or the like is considerably weakened by said threading and is easily broken or otherwise injured when dropped or permitted to fall to the floor.

Another object of the invention is to provide in a pipe of the character described having an outer bowl and stem, an inner bowl rigidly and fixedly held in said outer bowl for preventing the latter from becoming

overheated in use, and means for reinforcing the free end of said stem.

A further object of the invention is to provide in a pipe of the character described having an outer bowl and stem, an inner bowl of briar wood, or the like, rigidly and fixedly secured within said outer bowl for preventing the latter from becoming overheated, and a reinforcing sleeve of metal or the like provided in the free end of the stem for reinforcing the same and for receiving in threaded engagement therewith a mouthpiece or the like.

A still further object of the invention is to provide in a pipe of the character described, having a bowl and a stem, a metal tube having one end thereof rigidly secured to a mouthpiece or the like and being adapted to be received removably in the stem of said pipe, said tube extending throughout the full length of said stem and held in threaded engagement with said stem, thereby facilitating the ease and convenience with which the said pipe may be assembled.

A still further object of the invention is to provide in a pipe of the character described, a tube of metal, or the like, which is adapted for connecting the stem of said pipe to a mouthpiece and for reinforcing the free end of said stem at the point of connection between the stem and mouthpiece.

A still further object of the invention is to provide a pipe of the character described, having a bowl and a stem of a phenol resin compound, or the like, which bowl is adapted to be shrunk unto an inner bowl of briar wood, or the like, whereby a rigid and secure connection is obtained between the said inner and outer bowls.

With the foregoing and other objects in view, which will appear as the description proceeds, my invention consists in the construction, combination and arrangement of parts of my device whereby the objects contemplated are attained, as hereinafter more

fully set forth, pointed out in the appended claims, and illustrated in the accompanying drawings.

My invention is illustrated in one form of 5 a smoking pipe, but this selection is merely for the purpose of explaining the invention, and it will be understood that the invention can be embodied in any form of pipe for which it is or may be adapted.

10 In the accompanying drawings forming a part of this application and in which like numerals designate like parts throughout the several views:

Fig. 1, is a top plan view of a smoking pipe 15 embodying the invention;

Fig. 2, is a transverse vertical section taken on line 2—2 of Fig. 1, showing the pipe in assembled condition with the mouthpiece;

20 Fig. 3, is a detail side elevation of the metal tube connecting the mouthpiece to the pipe stem, one end thereof being connected to the mouthpiece, and

Fig. 4, is a transverse section of the inner bowl of the pipe.

25 Referring to the drawings, it will be seen that my invention contemplates in this embodiment a pipe having a bowl 10, and a straight stem 11, through which extends a smoke passage 12, to the bowl. The bowl 10, 30 and the stem 11, are made from a phenol resin compound, or the like, said bowl and stem being cut out of a block of said compound, as by brazing, or in any other suitable manner.

35 The said pipe bowl is reinforced by providing on the inside thereof a bowl 13, of briar wood, or the like, for the purpose of preventing the said outer bowl from becoming overheated and eventually cracking.

40 The inner bowl is adapted to be held rigidly and securely in the outer bowl, the fit between the two bowls being very snug whereby the possibility of the formation of air compartments therebetween will be eliminated.

45 In order to properly and securely position the inner bowl 13 in said outer bowl 10, the following method may be used, which method has been found to give very satisfactory results. The bowl 10, after the same

50 has been formed from the block of phenol resin compound, is heated so as to cause an expansion of the same. The bowl 13, is then positioned in said bowl 10, and the latter allowed to cool. The shrinking of the outer

55 bowl in cooling will cause the same to be shrunk on the inner bowl, assuring a close and snug fit between the two. If desired, a suitable adhesive substance may be provided between the said bowls for further aiding

60 in rigidly maintaining the same in assembled condition. An opening 14, is provided in the lower wall of the inner bowl 13, for communication with the smoke passage 12, provided in the stem 11.

65 A mouthpiece 15, having a smoke passage

16, is adapted to be associated with the pipe stem 11. The inner end of said mouthpiece may be provided with an internally threaded bore, indicated at 17, which bore is adapted to receive in rigid engagement therewith, an externally threaded end 18 of a tube 19, of metal, or other suitable material, the other end of said tube 19, being adapted to be received in the stem 11, and extend throughout the full length thereof, the mouth 20, of said tube, when the mouthpiece and stem are assembled, being positioned adjacent the opening 14, in the inner bowl 13. A portion of the outer periphery of the tube 19, adjacent the threaded end 18, is externally threaded as indicated at 21, said threaded portion 21, being adapted to be received in threaded engagement with an internally threaded sleeve 22, of metal, or the like. The said sleeve 22 is rigidly and fixedly secured in the free end of the stem 11, and is adapted for, not only receiving the tube 19, but also reinforces the end of said stem, whereby the liability of injury to said stem in falling is eliminated. The sleeve 22 may be secured to said stem 11, in a manner similar to that employed for securing the inner bowl 13 to the bowl 10, or in any other suitable manner.

It will be noted that my construction provides reinforcing for the pipe stem at the free end thereof where it is most needed, and it also reinforces the threaded end of the mouthpiece which is usually weak because of the threads provided therein. It will also be noted that the tube 19 is rigidly connected to the mouthpiece, thereby greatly facilitating the assembling of the several parts of the pipe.

From the foregoing description it is thought to be obvious that a smoking pipe 10 constructed in accordance with my invention is particularly well adapted for use by reason of the convenience and facility with which it may be assembled and operated, and it is also obvious that my invention is susceptible of some change and modification without departing from the principles and spirit thereof and for this reason I do not wish to be understood as limiting myself to the precise arrangement and formation of the several parts herein shown in carrying my invention into practice except as herein claimed.

What I claim and desire to secure by Letters Patent of the United States is:—

1. The method of making a smoking pipe of the character described which comprises, first cutting out of a block of a phenol resin compound, a pipe bowl and stem having a smoke passage therethrough, then heating the same to cause it to expand, then inserting into said first bowl an inner bowl of briar wood, and then allowing the same to cool, whereby the said outer bowl is shrunk on to the said inner bowl.

2. The method of making a smoking pipe
of the character described which comprises,
first cutting out of a block of a phenol resin
compound, a pipe bowl and stem having a
5 smoke passage therethrough, then heating
the same to cause it to expand, then inserting
into the free end of said stem an internally
threaded metal sleeve, and then allowing the
same to cool, whereby the end of said stem is
10 shrunk on to the metal sleeve.

In testimony whereof, I affix my signature.

JEROME GEVIRMAN.
